UNITED STATES PATENT OFFICE.

EMIL RITTER VON SKODA, OF PILSEN, AUSTRIA-HUNGARY.

BREECH-LOADING ORDNANCE.

SPECIFICATION forming part of Letters Patent No. 449,711, dated April 7, 1891.

Application filed September 22, 1890. Serial No. 365,757. (No model.)

To all whom it may concern:

Be it known that I, EMIL RITTER VON SKODA, a subject of the Emperor of Austria, residing at Pilsen, in the Province of Bohemia, in the

5 Empire of Austria-Hungary, have invented certain new and useful Improvements in Breech-Loading Guns; and I do hereby declare the following to be a full, clear, and exact description of the invention, such as will 10 enable others skilled in the art to which it appertains to make and use the same, reference being had to the accompanying drawings, and to letters of reference marked thereon, which form a part of this specification.

15 The invention relates to breech-loading ordnance, and more especially to that class of ordnance in which the breech-block has motion in a plane at right angles to the axis of the breech-chamber, and in which the 20 firing-pin is contained within the breech-block.

The object of my invention is to simplify 25 the breech mechanism; and the invention consists in structural features and combinations of parts, as will now be fully described, reference being had to the accompanying drawings, in which—

Figure 1 is a sectional elevation of so much 30 of the breech end of a gun as will be necessary to illustrate my invention. Fig. 2 is a vertical transverse sectional elevation of the same. Figs. 3 and 4 are vertical axial sectional elevations of Fig. 1, showing the firing mechanism in its position after firing and 35 ready for firing, respectively. Fig. 5 is a sectional detail view illustrating a coiled mainspring in combination with a tubular firing-pin in lieu of a leaf-spring, as shown in the above-described figures. Figs. 6 and 7 are 40 views similar to Figs. 1 and 2, respectively, illustrating the breech-block and firing-pin actuating mechanism as arranged axially of the breech-block. Figs. 8 and 9 are like views illustrating the arrangement of the 45 shell-extractor relatively to the breech-block, which latter is not shown in Fig. 9; and Fig. 10 is a detail elevation in which the arrangement of the sear or main lever is shown as engaging the firing-pin from below.

50 Like letters of reference indicate like parts wherever such may occur in the above draw-

ings, and as thereon indicated A is the breech-block that has motion within a chamber in rear of the breech in a plane at right angles to the axis of the gun.

55

a is the lever for actuating the breech-action, which lever is fulcrumed at a'. This lever is practically a two-armed lever, whose shorter arm a² is pivotally connected with the breech-block A by means of a link B and a 60 pin or stud b, that projects from the upper end of said link into the breech-block, as shown in Figs. 1 to 4, inclusive. The pin b has motion within its bearing in the breech-block and has a radial lug b', adapted to engage the lug c, Figs. 2, 3, and 4, on the firing-pin C, that is contained in a cylindrical chamber formed axially in the breech-block.

65 By the side of the lug c on the firing-pin is formed a second lug c', Fig. 2, adapted to be 70 engaged by a detent-lever E, that is fulcrumed at e in a vertical recess formed in the breech-block A in rear of the firing-pin C. (See Figs. 2, 3, and 4.) The lever E is constructed in the form of an angle-lever, the shorter horizontal arm e² of which has a locking-shoulder 75 that engages the lug c' on the firing-pin C. To the vertical arm e' of lever E, which arm projects downwardly and out of the breech-block A, is secured the mainspring d, the free 80 end whereof has bearing on the rear end of the firing-pin C, as shown. The detent-lever E is simply suspended upon its pivot or fulcrum pin e, and has a stop-arm e³, that bears 85 against an abutment or shoulder formed in the breech-block, the lever being thus firmly braced at opposite ends against the stress of the mainspring d.

85 From the description of the construction of the breech-action it will be seen that the 90 parts are very few and simple and that the movement of the lever-arm a² and link B is very limited as compared with the movement of like parts in guns of this class.

95 The shell-extractor consists of two levers G, fulcrumed on a pin g below the breech, and each of said levers is provided with a pin g', that takes into a vertical groove g², formed in the opposite sides of the breech-block A, the upper end of said groove being 100 curved rearwardly, so that the movements of the extractor are controlled by those of the

breech-block itself instead of being controlled by independent devices.

By reference to Figs. 8 and 9 it will readily be understood that when the operating-lever 5. *a* is moved from its position shown in full lines in Fig. 1 to that shown in dotted lines in said figure the link *B* will draw the breech-block *A* down, not in a line perpendicular to the axis of the gun, but in a line that inclines more or less rearwardly, so that the extractor-levers *G* will be moved rearwardly to the same extent for the purpose of loosening or starting the empty shell in the breech, and as the pins *g'* on the said extractor-levers enter the rearwardly-curved portion of the grooves *g*² the extractor-levers will also move rearwardly, and the empty cartridge-shell will be extracted from the breech and ejected, at which time the breech-block will have 15 reached its lowermost position, as shown in dotted lines in Fig. 1, and the pins *g'* will lie in the upper end of the grooves *g*². When the lever *a* is returned into its normal position for the purpose of closing the breech, 20 the lateral arms *g*³, Fig. 9, of the extractor-lever will lie in close contact with the rear face of the breech-chamber, so that when a cartridge is inserted into said chamber its flange will bear upon said lateral arms *g*³ of 25 the extractor-lever.

The mechanisms above described may be variously modified in their construction and in their relative arrangement without departing from the nature of my invention. For 35 instance, but a single extractor-lever *G* may be employed instead of two, and when two such levers are employed, as described above, one of them only may be connected with the breech-block instead of both. On the other 40 hand, the extractor lever or levers may be fulcrumed above instead of below the breech-block, in which case the curved portion of the guide-groove *g*² will be at the lower end of said breech-block instead of being at the 45 upper end.

Instead of a leaf-mainspring *d*, a coiled mainspring may be used, in which case I preferably provide the firing-pin *C* with a socket for the reception of the free end of the said 50 coiled spring, as shown in Fig. 5. Furthermore, the lug *c'* may be formed on the lower portion of the firing-pin and the horizontal arm *e'* of the detent-lever *E* located accordingly, as shown in Fig. 10, in which case the lever 55 *E* is actuated by rearward traction instead of pressure applied in a forward direction. Furthermore, the connections between the breech-block *A* and the lever *a* may be arranged axially of the breech-block, as shown in Figs. 6 and 7, the link *B* being in this case constructed in the form of a two-armed lever 60 adapted to engage the lug *c*, which projects from the lower portion of the firing-pin *C*. Finally, the body of the firing-pin *C* need not 65 necessarily be of cylindrical form in cross-section, but may be of a polygonal form.

As shown in Fig. 6, the trigger *f* is a cam on

a pin provided with crank, said cam having bearing on the free end of the detent-lever *E*.

The advantages of the described breech-action consist in the great simplicity and the small number of the co-operative parts, all of which may be made very strong; also, in that the arrangement of the co-operative devices admits of the use of a very short firing-pin 70 wholly concealed or contained within the breech-block, and by providing a positive connection between the breech-block and shell-extractor and arranging the latter so as to have motion on a fixed pivot the operation of the said extractor is rendered absolutely certain, it being wholly controlled by the breech-block. Finally, by connecting the shell-extractor with the breech-block the operation of the former is rendered more accurate than 75 would be the case otherwise.

Having described my invention, what I claim is—

1. In a breech-loading gun in which the breech-block has a traversing motion in a direction at right angles to the axis of the gun, the combination, with the breech-chamber and said breech-block provided in one of its lateral faces with a vertical groove having a rearwardly-curved end, of a shell-extractor 90 lever having motion on a fixed pivot in a plane at right angles to the plane of motion of the block, said lever having a pin or stud projecting into the groove of the block, for the purpose set forth.

2. In a gun of the class described, the combination, with the breech-chamber, a vertical slot in rear thereof, the breech-block having motion in said slot, an actuating-lever having two arms of unequal length, and a link pivotally connected with the breech-block and the short arm of the lever, of a firing-pin contained within the breech-block, a spring having bearing on the end of the firing-pin, and an actuating device controlled by the lever and link for imparting motion to the firing-pin against the stress of its spring, for the purpose set forth.

3. In a gun of the class described, the combination, with the breech-chamber, a vertical slot in rear of said chamber, the breech-block having motion in said slot, a lever having two arms of unequal length, and a link pivotally connected with the block and short arm of the lever, of a firing-pin contained within the breech-block, a spring having bearing on the end of the firing-pin, an actuating device controlled by the lever and link for imparting motion to the firing-pin against the stress of the spring, and a detent for locking the firing-pin against motion under the stress of its spring, the said actuating device, spring, and detent being also contained within the breech-block, for the purpose set forth.

4. In a gun of the class described, the combination, with the breech-chamber, a vertical slot in rear thereof, the breech-block having motion in said slot, a lever having arms of

unequal length, and a link pivotally connected with the block and short arm of the lever, of a firing-pin contained within the breech-block, a spring having bearing on the rear end of the firing-pin, an actuating device controlled by the lever and link to impart motion to the firing-pin against the stress of its spring, and a detent to which the heel of the spring is secured, adapted to lock the firing-pin against motion under the stress of its spring, said actuating device, spring, and detent being contained within the breech-block, for the purpose set forth.

5. In a gun of the class described, the combination, with the breech-chamber, a vertical slot in rear thereof, the breech-block having motion in said slot, a lever having two arms of different length, and a link pivotally connected with the breech-block and the shorter 10 arm of the lever, of a firing-pin, a detent consisting of an angle-lever suspended from a pin within the breech-block in rear of the firing-pin, a spring interposed between the detent and firing-pin and having bearing on 15 both, said detent being adapted to lock the firing-pin against motion under the stress of the spring, and an actuating device controlled by the lever and link for moving the firing pin against the stress of its spring, for the 20 purpose set forth.

6. In a gun of the class described, the combination, with the breech-chamber, a vertical slot in rear thereof, the breech-bolt, and a spring-actuated firing-pin contained within 25 the bolt and having a projecting abutment, of a lever having two arms of unequal length, a link provided with a pivot-pin having bearing in the breech-bolt and being provided with a radial lug adapted to engage the abut-

ment on the firing-pin, and a pivotal connection between the link and short arm of the lever, for the purpose set forth.

7. In a gun of the class described, the combination, with the breech-chamber, the breech-block, a spring-actuated firing-pin contained in said block and provided with a shoulder or abutment, a two-armed lever *a*, and a link *B*, pivotally connected with the block, the pivot-pin of the link being provided with a lug or radial arm having bearing on the abutment of the firing-pin to move the same against the stress of its spring, of the angle-lever *E* and a spring interposed between said lever and the pin and having bearing on both, as and for the purposes set forth.

8. In a gun of the class described, the combination, with the breech-chamber, the breech-block, a spring-actuated firing-pin contained in said block and provided with a shoulder or abutment, a two-armed lever *a*, and a link *B*, pivotally connected with the block, the pivot-pin of the link being provided with a lug or radial arm having bearing on the abutment of the firing-pin to move the same against the stress of its spring, of the angle-lever *E* and the flat spring *d*, having its heel connected with the vertical arm of the lever and its free end in contact with the rear face of the firing-pin, substantially as and for the purposes set forth.

In testimony whereof I affix my signature in presence of two witnesses.

EMIL RITTER v. SKODA.
